2 Sheets-Sheet 2

INVENTOR:

Thomas E. Hunt

By John Howard (McIlroy)
HIS ATTY.

UNITED STATES PATENT OFFICE.

THOMAS E. HUNT, OF CHICAGO HEIGHTS, ILLINOIS, ASSIGNOR TO QUAKER MANUFACTURING COMPANY, OF CHICAGO, ILLINOIS, A CORPORATION OF ILLINOIS.

IRONING MACHINE.

Application filed February 20, 1922. Serial No. 537,714.

To all whom it may concern:

Be it known that I, THOMAS E. HUNT, a citizen of the United States, and a resident of Chicago Heights, in the county of Cook and State of Illinois, have invented certain new and useful Improvements in Ironing Machines, of which the following is a specification.

My invention is concerned with ironing machines, and resides in a novel construction of the shoe whereby I can make its operating surface of a sheet of comparatively thin metal, and still have it hold its shape in spite of the tendency of the heat to warp it away from the roll, this novel construction cheapening the cost while improving the quality.

To illustrate my invention, I annex hereto two sheets of drawings, in which the same reference characters are used to designate identical parts in all the figures, of which,—

Fig. 1 is a rear elevation of an ironing machine employing my invention;

Fig. 2 is a sectional view as seen on the line 2—2 of Fig. 1;

Fig. 3 is a detail in section, on an enlarged scale and with parts broken away, on the line 3—3 of Fig. 2;

Fig. 4 is a perspective view of the shoe, with the sheet-metal heat deflector removed, but its position indicated in dotted lines;

Fig. 5 is a view of the under side of the shoe, with the retaining cover and the heat-insulating material removed, on a much larger scale than Fig. 4;

Fig. 6 is a detail in section on the line 6—6 of Fig. 5;

Fig. 7 is a similar view, on the line 7—7; and

Fig. 8 is a view similar to Fig. 6 and on the same section line, but showing the iron adapted for heating it by gas, instead of by electricity, as in Figs. 5, 6 and 7.

While my invention may be applied to any type of ironing machine employing a rotating roll, I have shown it as applied to the specific ironing machine shown in my application for Patent No. 482,921, filed July 7, 1921, and in this machine I employ a pair of generally A-shaped end frames 10, which are connected by suitable spacing rods, and which have journaled in the upper ends thereof the ironing roll 11, which co-

operates with the concave shoe 12, heated by the flame from the burner 13, and fulcrumed by means of a pair of swinging frames 14 to the end frames at 15. In use, these rolls 11 have to be rotated, and for this purpose I provide the electric motor 16, which is supported by being bolted to the upper portion of the spring plate 17, which is secured by bolts 18 passed through the lower end thereof and co-operating with the cross piece 19 of the frame 10. The armature shaft 20 of the motor has secured upon its outer end a belt pulley 21, which is connected by the belt 22 with a belt wheel 23, which is secured on the outer end of the worm shaft 24, suitably journaled in bearings carried by the end frame 10, and having between said bearings a worm 25, which meshes with a worm gear 26 journaled on a stud shaft projecting outwardly from the end frame 10. The worm gear 26 has formed integrally therewith or rigidly secured thereto a sprocket gear 27, which is connected by a sprocket chain 28 with the sprocket wheel 29 secured on the end of the shaft 30 to which the roll 11 is secured.

It will be obvious that when power is applied to the motor, the latter rotates at a high speed, and the train of gearing shown and described serves to rotate the roll 11 at the comparatively low speed needed in such machines. The novel mounting of the motor upon the under side of this spring plate 17 serves the desirable functions of producing a simple and inexpensive mounting and one in which there is no objectionable vibration or noise, as that is all taken up by the spring action of the plate 17. It will also be noted that the general trend of the plate 17 is such that the natural spring of the plate serves to keep the belt 22 taut, if it has been properly adjusted to start with, and if the belt contracts, the plate 17 can yield enough more to prevent any possible breakage of the belt.

I have found that sometimes the users of these ironing machines do not know just when the iron is of the proper temperature for the best results, and this is especially true where gas is used for heating the iron, as the pressure varies, as well as the quality of the gas, and I provide an indicator to show if the iron is too cold, in which case

more gas will be turned on; or if it is too hot, in which case it can be turned off. To this end, I employ the construction shown in Fig. 2, where 12 is the shoe, which is heated by the gas burner 13, preferably enclosed by the sheet-metal casing 31 extending the length of and adapted to be secured to the inner edges of the under side of the shoe. A sheet-metal shield 32 is also provided to deflect some of the heat from the wooden feed-board 33, which is secured on the horizontal upper surface of the shoe-supporting brackets or end pieces 14 pivoted at 15. For the purpose of forming a simple and efficient indication of the temperature of the shoe, I secure a pair of iron rods 34 in the castings 14, in the position shown in Fig. 2, these rods being accurately adjusted in place by having their threaded outer ends passed through an unthreaded aperture 35 in the casting and secured in any desired adjustment by the nuts 36 threaded on the rod on both sides of the casting. The inner ends of these rods have slots therein in which is placed the needle 37, which has two apertures therein through which pass the two pins 38 passed through and secured in the ends of their respective rods 34. Upon the rounded upper edge of the shoe 12 or on the adjacent edge of the table 33, as may be preferred, I place the co-operating graduations or marks, which may be either a scale or words, such as "Cold," "Hot" and "Too hot" as shown.

The operation of this feature of my invention is as follows: The shoe 12, being directly exposed to the heat, expands, and as it expands, the end castings 14 are shoved apart. This results in the rods 34 being drawn apart, so that the needle 37, which, when the iron is cold, stands in the position indicated in dotted line in Fig. 3, is swung to the left, and if the iron is of the right temperature, it stands at the word "Hot," or substantially so. In case the iron gets too hot, the continued expansion of the shoe draws the needle to the warning position "Too hot." This construction furnishes a very simple and very efficient thermostatic indicator for the temperature of the shoe.

The third feature of my invention is illustrated in Figs. 4 to 8, and is concerned with the construction of the shoe 12, the heat-transmitting portion of which consists of a plate of comparatively heavy sheet-steel formed into the cross section best shown in Figs. 6 to 8, where it will be seen to have one U-shaped flange 39 on one edge and the angular flange 40 on the other edge. The sheet-metal cover 31 is preferably semicircular in transverse cross section and has one edge secured to the flange 39 by the bolts 41, while the other edge is secured to the flange 40 by the bolts 42. The end castings 14 are provided with the horizontally

extending flanges 43, which are curved to correspond to the convex side of the shoe, which is secured thereto by the bolts 44. The flange is preferably provided with the triangular brace portions 45 to give additional rigidity to the angle-shaped cross-section of the casting 14 at this point. The flange 43 is also provided with the pair of substantially rectangular recesses 46, which are provided for all irons, although they have a function only where the iron is heated by electricity, as will be hereinafter described.

Where the iron is heated by gas, as illustrated in Figs. 2, 4 and 8, the truss rod 47 is located in the position best shown in Figs. 4 and 8, where it will be seen to extend through apertures in the castings 14 outside of the sheet-metal casing 31, and to be held firmly relative to said end castings 14 by the nuts 48 screwed on the ends thereof. The action of this rod 47 is as follows: The plate 12, constituting the heat-transmitting portion of the shoe, is, as previously stated, composed of sheet metal and is much lighter in weight than the cast shoes that have heretofore been employed in order to give the necessary rigidity to the shoe and prevent its warping under the action of heat. The tendency of this shoe without the rod 47, as I have found by experience, is to bow away a little from the roll 11 when it becomes heated, and while this amount is not great, it is sufficient to interfere with the thorough ironing of thin goods, and to prevent this difficulty, I employ the rod 47, as described, which, being further away from the burners 13, and not having the flame directed thereon, is not heated to the same degree as the shoe 12, and consequently does not expand so much. The result of this rod becoming relatively shorter than the shoe 12 is that it tends to keep its edges of the casting 14 closer together than the upper edges to which the shoe 12 is attached, with the result that there is a tendency for the shoe 12 to bow in the opposite direction from that heretofore recited, i. e., toward the roll 11, instead of away from it. This action neutralizes the other tendency, and keeps it either absolutely straight, or, if there is any variation, the bowing is toward the roll, which is not particularly objectionable, as the bulk of the ironing is done at the middle portion of the roll anyway. By the employment of this rod, I have found that I can get the desired rigidity of the shoe and prevent its warping so as to interfere with the successful operation of the iron. In the construction for the electrically-heated shoe shown in Figs. 5, 6 and 7, instead of locating the rod 47 in the position shown in Fig. 8, I place the corresponding rod 47* inside of the cover 31, and as it is in this position closer to the shoe 12, and does not have so

effective a pull as it does in the position farther away, illustrated in Fig. 8, I reinforce this action by screwing the short bolt 49 into the back of the shoe 12 at the center thereof, and preferably lock it in position by the nut 50. The head of the bolt 49 has a recess 51 therein, into which fits the rod 47^a, the bolt 49 as thus arranged operating somewhat like the post of the ordinary king-post truss.

The final feature of my invention resides in the construction I employ for heating the iron by electricity, and this consists in a pair of elongated, rectangular heating elements 52, which may be of any suitable construction, and which have their ends extended into the recesses 46, and are provided with the binding posts 53, to which the necessary conductors 54 are connected. The heating elements are held in place by the sheet-metal plate 55, which has the cross section shown in Figs. 7 and 8, and is adapted to hold the elements 52 firmly against the back of the shoe. This plate 55 is held by two or more screws 56 passed through apertures therein and threaded into the under side of the plate 12. In order to insulate the rod 47^a from the heat of the elements 52, and also to retain the heat in the shoe on that side, I fill all the space within the cover 31 and surround the rod 47^a with some heat-insulating material 57, preferably mineral wool, the material being in-

dicated somewhat diagrammatically by dots to prevent obscuring the mechanical details 35 seen back of it.

While I have herein shown and described my novel temperature indicator for the shoe, I do not herein claim the same, as it is covered in my divisional application No. 40 590,228, filed September 25, 1922.

While I have shown and described my invention as embodied in the form which I at present consider best adapted to carry out its purposes, it will be understood that it is 45 capable of modifications, and that I do not desire to be limited in the interpretation of the following claim except as may be necessitated by the state of the prior art.

What I claim as new, and desire to secure 50 by Letters Patent of the United States, is:

In an ironing machine, the combination with a metallic plate concaved on its outer surface to fit against a roll, of rigid end pieces secured to and extending from the end thereof; a rod connecting said end pieces, electric heating elements disposed against the convex surface of the plate, means for holding the electric heating elements in place, and heat-insulating material between the electric heating elements and the rod, substantially 55 as and for the purpose described.

In witness whereof, I have hereunto set my hand this 16th day of February, 1922.

THOMAS E. HUNT.
